James Herman, of Lancaster Ohio.

Letters Patent.

The schedule referred to in these Letters Patent, and sealing part of the same, containing a description in the words of the said James Herman, himself of his improvement in the making of grooving planes called the roller grooving planes for flooring and other purposes.

To all persons to whom these presents shall come.

James Herman of the town of Lancaster County of Fairfield in the State of Ohio. Sends Greeting. Be it known that the said James Herman, have invented a new and useful improvement not known or used before in the making or manufacturing of the grooving planes used by carpenters and house joiners which invention, and the manner of using it is as follows. This improvement in the usual grooving planes consists in having two or more metal rollers in the face of the tongueing plane and also two or more rollers in the faces of each of the faces of both tongueing plane and groove to run in metal boxes or on pivots or guides, and also the addition of two extra bills for the purpose of chamfering the corners of the tongue, and also the groove, one of the extra bills is placed on the tongueing bill in the manner of the cap on a double bill, the other extra bill in the grooving plane is placed in front of the grooving bill between the grooving bill and the forward end of the plane for further securing (accompanying this) be witness whereof I have hereunto subscribed my name this 27th day of May A.D. 1835
